US00D558784S

(12) **United States Design Patent** (10) **Patent No.:** **US D558,784 S**
Andre et al. (45) **Date of Patent:** **** Jan. 1, 2008**

(54) **ELECTRONIC DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Jonathan P. Ive**, San Francisco, CA (US); **Steve Jobs**, Palo Alto, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US)

(73) Assignee: **Apple, Inc.**, Cupertino, CA (US)

(**) Term: **14 Years**

(21) Appl. No.: **29/269,781**

(22) Filed: **Dec. 8, 2006**

Related U.S. Application Data

(63) Continuation of application No. 29/242,458, filed on Nov. 9, 2005, now Pat. No. Des. 538,822, which is a continuation of application No. 29/208,302, filed on Jun. 24, 2004, now Pat. No. Des. 516,576.

CLAIM

We claim the ornamental design for an electronic device, substantially as shown and described.

DESCRIPTION

FIG. 1 is a perspective view of an electronic device showing our new design;

FIG. 2 is a front view for the electronic device.

FIG. 3 is a rear view for the electronic device.

FIG. 4 is a top view for the electronic device.

FIG. 5 is a bottom view for the electronic device.

FIG. 6 is a right side view for the electronic device; and,

FIG. 7 is a left side view for the electronic device.

The broken lines, which define the boundary of the claim, form no part thereof.

1 Claim, 3 Drawing Sheets

UNITED STATES PATENT AND TRADEMARK OFFICE
CERTIFICATE OF CORRECTION

PATENT NO. : Des. 558,784 S
APPLICATION NO. : 29/269781
DATED : January 1, 2008
INVENTOR(S) : Andre et al.

Page 1 of 1

It is certified that error appears in the above-identified patent and that said Letters Patent is hereby corrected as shown below:

On the title page of the patent, in column one, under section (73) Assignee, "Apple, Inc." should be replaced with --Apple Inc.--

Signed and Sealed this

Twenty-ninth Day of April, 2008

JON W. DUDAS
Director of the United States Patent and Trademark Office
